(57) **CLAIM**

The ornamental design for a front seat, as shown as described.

DESCRIPTION

FIG. 1 is a back view of a front seat.

FIG. 2 is a bottom view of the front seat of FIG. 1.

FIG. 3 is a front view of the front seat of FIG. 1.

FIG. 4 is an isometric view of the front seat of FIG. 1.

FIG. 5 is a left-side view of the front seat of FIG. 1.

FIG. 6 is a right-side view of the front seat of FIG. 1; and, FIG. 7 is a top view of the front seat of FIG. 1.

The broken lines show in the drawings are included for purposes of illustrating boundaries of the article and form no part of the claimed design.

1 Claim, 7 Drawing Sheets

FIG. 1

FIG. 2

FIG. 3

FIG. 5

FIG. 6

FIG. 7
